UNITED STATES PATENT OFFICE

1,983,695

METHOD OF DECORATING SHEET RUBBER

Frank Fenton, Akron, Ohio, assignor to The B. F. Goodrich Company, New York, N. Y., a corporation of New York

Application August 23, 1933, Serial No. 686,391

2 Claims. (Cl. 41—24)

This invention relates to the ornamentation of sheet rubber.

The principal object of the invention is to provide coloring of the sheet in a determinate 5 pattern.

Other objects will appear from the following description and drawing.

Of the drawing:

Fig. 1 is a cross-sectional view of the printing apparatus used taken on a vertical plane.

Fig. 2 is a section on line 2—2 of Fig. 1 showing the sheet of material before and after printing, parts of the sheet and of the machine being broken away.

15 Referring to the drawing, in practicing the invention a sheet of soft vulcanized rubber 10 is molded from rubber composition to provide a surface having raised portions 11 defined by depressed areas 12 therebetween. Any desired 20 design may be employed. In that shown in the drawing the depressed portions are grooves intersecting each other at right angles to define raised rectangles 11 therebetween.

25 After the sheet has been vulcanized to provide the desired surface design it is passed between rollers such as 13, 14, one of which is coated with ink or other coloring matter different from the color of the sheet. A colored ink containing rubber is preferred.

30 In order to provide for continuous printing means are provided for progressively coating the inked roll 14. A suitable device comprises a

frame 15 in which the roller 14 is journaled, a roll 16 also journaled in the frame in position to contact with roll 14 in rolling engagement and a pan 17 to contain the ink 18 in which the roll 16 is partially immersed.

5 A doctor bar 19 is provided to contact with the roll 16 and distribute the ink uniformly.

The pressure roll 13 is journaled in boxes 20 slidably mounted in the frame 15 and screws 21 are provided to force the roll 13 toward the 10 roll 14. Various modifications of the effect may be obtained by varying the pressure whereby the raised portions of the sheet are caused to flatten out and receive a coating over a larger area.

I claim:

1. The method of making an ornamental sheet of resilient material which comprises permanently forming a sheet of resilient rubber having raised portions on one face thereof, from a suitable compound of one color, and changing 20 the appearance of the sheet by applying ink of another color to the raised portions of the sheet.

2. The method of making an ornamental sheet of resilient material which comprises permanently forming a sheet of rubber to provide 25 a design having raised and depressed portions, and applying a coating of coloring matter to the raised portions by application of pressure without coating the depressed portions.
